BUILDING CONSTRUCTION

Dean D. Crandell, Buffalo, N. Y., assignor to
National Gypsum Company, Buffalo, N. Y.

Application September 24, 1938, Serial No. 231,572

2 Claims. (Cl. 72—16)

This invention relates to an improvement in building construction and particularly to an improved reinforced building element.

In building construction it has been conventional to employ monolithic slabs arranged in approximately abutting relation and disposed against structural frame-work to form building walls. The problem of reinforcing or covering the joints occurring at the meeting edges of such slabs has been variously approached.

The building slabs referred to herein frequently take the form of lath units of plaster, fiber or other suitable material and are supported against building frame-work comprising spaced supporting elements such as the usual scantlings or studding. In employing units of the plaster lath type in building construction, a coating of plaster is usually applied over the entire face of the lath after the lath has been applied and in such manner as to seal the joints occurring at the meeting edges. It has previously been proposed to preliminarily cover such meeting edges with a metallic or other reinforcement. In general such reinforcements have been assembled with the plaster lath and the other elements of the construction at the time and at the place where the wall is being constructed.

Some suggestion of initially providing plaster lath elements with edge reinforcing elements has been made but it is essential that the plaster lath units be capable of cutting and fitting and such reinforcements as have heretofore been proposed have been objectionable since they have unduly interfered with cutting and fitting the plaster lath units to such an extent as to render them impractical and unsatisfactory.

In the plaster lath units of the present invention and the building construction resulting therefrom, a relatively infrangible lath edge reinforcement is provided and so arranged as not to interfere with normal sizing and fitting of plaster lath units. This object is attained in general by so proportioning and locating a plurality of plaster lath reinforcements as to anticipate and take into account the normally arising necessity for cutting or dividing of plaster lath units.

One form of the instant invention is illustrated in the drawing in which

Fig. 1 is an elevational view partly in cross-section of a wall faced with plaster lath and Fig. 2 is a perspective view of the proposed new building element.

The exact proportioning of building elements and reinforcements therefor will, according to 55

the teaching of the present invention, be adjusted to suit prevailing trade requirements but as a practical example and for the purpose only of delineating the invention, I shall refer to plaster lath units which are 48" in length and designed for use with studding spaced at a pitch of 16". The spacing of the studding may of course be any practical figure and the overall length of the plaster lath may be any suitable multiple of 10 the pitch of the studding.

As illustrated in the drawing, a plaster lath element 10 of a length substantially equal to three times the pitch of the studding is disposed with its vertical edges secured to studs 11 and 12, there being two intervening studs 13 and 14 to which the plaster lath units may or may not be intermittently secured. The lath units of the tiers occurring either above or below a given tier of lath units are preferably disposed so that their vertical edges are in staggered relation to the vertical edges of the given tier as such construction has been found to be superior from the standpoint of rigidity and permanence. This is exemplified in the disposition of the lath indicated at 15 in the second tier of Fig. 1. It will easily be seen that, if for no other reason, such staggering of the lath units requires the use of lath units of different lengths whenever a vertical wall, as the wall 16 of Fig. 1, is encountered.

In the illustrated instance full plaster lath units of a length equal to three times the pitch of the studding may be used in the second tier as at 17 but plaster lath units 18 and 19, of a length equal to only twice the pitch of the studding, must be used in the top and bottom tiers respectively. Plaster lath units, unless complicated by relatively less frangible reinforcements, may be sawed like ordinary boards.

40 The present invention contemplates the provision of a series of edge reinforcing elements so spaced as not to interfere with normal sawing or other severing of plaster lath units. Experience, and in fact an inspection of Fig. 1 of the drawing, teaches that such severing, in the great majority of instances, must occur at points coincident with the occurrence of studding. In other words, the cutting usually is desired at points along the lengths of the lath which are spaced from the end of the lath a distance equal to the pitch of two or more studs.

An example of a building unit of the present invention is found in Fig. 2 where a relatively frangible slab 20, of plaster, fiber board or other suitable material, has secured to one of its edges

a plurality of less frangible and, in the present instance, reticulated reinforcing elements 21. The reinforcing elements 21 are secured to the slab 20 as by staples 22 and are spaced at a pitch equal to the pitch of standard studding so that a saw or other severing means may pass between the relatively infrangible reinforcements at any desired studding line.

The length of the reinforcing elements may be varied but most satisfactory results are achieved by making their length only slightly less than the pitch of the studding, thereby permitting passage of a cutting instrument between the reinforcements without greatly interrupting the continuity of the line of reinforcement.

As seen in Fig. 1 when either a full size or severed plaster lath unit is placed against building frame-work, the reinforcing elements will project beyond one edge of their associated building element and onto an adjacent building element. Such projecting edge is normally secured to the adjacent building element by nails or other fastening devices as at 23 and the construction of the reinforcement is such as to readily lock into a subsequently applied coating of plaster indicated in Fig. 1 at 25.

While a single specific application of the principles of the present invention has been illustrated and described, it is to be understood that the invention is in no way limited excepting as 30 by the appended claims.

What is claimed is:

1. As an article of manufacture, a building element comprising a lath panel and a plurality of elongate reinforcing elements comprising a part of said article and being disposed along one edge thereof in spaced end to end relation, said reinforcing elements being flat, reticulated members secured against the plaster receiving surface of said lath and having longitudinal marginal portions projecting therefrom to overlie co-operating adjacent lath elements and the several reinforcing elements being of a length less than the pitch of conventional studding and spaced from each other at a pitch substantially equal to the pitch of conventional studding whereby the lath may be secured to studding with the reinforcing elements disposed intermediate each pair of studs.
2. In building construction, the combination of 20 studding, panel-like lath elements disposed thereagainst, and reinforcing elements forming a part of each lath element along an edge thereof extending transversely of said studding, said reinforcing elements being slightly less in length than the pitch of the studding and disposed medially between each pair of studs, whereby the panel-like elements may be cut along lines between adjacent reinforcing elements to size equal to multiples of the pitch of the studding without severance of said reinforcing elements.

DEAN D. CRANDELL.
